(57) **CLAIM**

The ornamental design for a clip, as shown and described.

DESCRIPTION

FIG. 1 is a front perspective view of our clip.

FIG. 2 is a bottom view of our clip.

FIG. 3 is a top view of our clip.

FIG. 4 is a left side view of our clip.

FIG. 5 is a right side view of our clip.

FIG. 6 is a front view of our clip; and,

FIG. 7 is a back view of our clip.

The broken lines illustrate environmental features that form no part of the claimed design.
